UNITED STATES PATENT OFFICE

116,094

DESIGN FOR AN AIRPLANE

Clarence L. Johnson, Burbank, Calif., assignor to
Lockheed Aircraft Corporation, a corporation
of California

Application November 10, 1938, Serial No. 81,000

Term of patent 14 years

To all whom it may concern:

Be it known that I, Clarence L. Johnson, a citizen of the United States, residing at Burbank, in the county of Los Angeles and State of California, have invented a new, original, and ornamental Design for an Airplane, of which the following is a specification, reference being had to the accompanying drawing, forming a part thereof.

Fig. 1 of the drawing is a perspective view of an airplane embodying the new design as it would

appear from a point off to the side and slightly forward and above the airplane while the latter would be in flight;

Fig. 2 is a side elevation of the airplane;
Fig. 3 is a front elevation thereof; and
Fig. 4 is a plan view of the subject airplane.

I claim:

The ornamental design for an airplane, substantially as shown.

CLARENCE L. JOHNSON.
